UNITED STATES PATENT OFFICE.

LOUIS A. PFEIFFER AND LYMAN D. STAPLES, OF SAN FRANCISCO,
CALIFORNIA.

OIL-BURNER.

SPECIFICATION forming part of Letters Patent No. 706,341, dated August 5, 1902.

Application filed November 13, 1901. Serial No. 82,135. (No model.)

To all whom it may concern:

Be it known that we, LOUIS A. PFEIFFER and LYMAN D. STAPLES, citizens of the United States, residing in the city and county of San Francisco, State of California, have invented an Improvement in Oil-Burners; and we hereby declare the following to be a full, clear, and exact description of the same.

Our invention relates to an apparatus for the proper combustion of hydrocarbon oils to be used for generating heat for various purposes.

It consists of concentric annular passages through which oil and steam are transmitted, having converging discharge ends at which point the two are brought together before being delivered to the burner. In conjunction with the tubes forming the annular passages are peculiarly-shaped ends or supports to which the tubes are secured and through which inlet and discharge passages are formed.

Our invention further consists in a means for adjusting the discharge-cones with relation to each other, so as to regulate the amount and proportion of oil and steam at the discharge and mixing end.

The invention also comprises details of construction, which will be more fully explained by reference to the accompanying drawing, in which the figure is a longitudinal section through the burner.

One object of our invention is to retain the steam under boiler-pressure and heat in a chamber inclosing that through which the oil flows and to mix the two at this high temperature within the burner-chamber, with the resultant advantages of the higher heat and drier steam.

As illustrated in the present drawing, the apparatus consists of an outer tube A and an inner tube B and in conjunction with these of a casting 2, by which the rear ends of the tubes are supported and through which the steam and oil inlets pass, and the casting 3, which supports the outer or discharge end and in conjunction therewith forms the conical discharge-passage and regulator. The blocks 2 and 3 may be cast or made of any suitable or desired metal. The block 2 has flanges 4 and 5 projecting from opposite ends

of the main body. The outer and larger tube A is screwed into the exterior flange, extending therefrom toward the discharge. To the flange 5 is screwed the cap 6, which closes 55 the rear end and forms an oil-chamber behind the part 2. The central portion of 2 has an opening through it of sufficient diameter to allow the pipe B to pass, and the joint formed where this pipe passes through 2 is made 60 tight by packing, as at 7, and a gland 8, through which the pipe passes, said gland being screwed down upon the packing sufficiently to make a tight joint.

Through the lower part of block 2 a passage is made, as shown at 9, and this serves for the admission of the oil into the chamber previously described as being formed at the rear of 2. 10 is a similar passage shown on the opposite side of the block 2, through 70 which steam is admitted into the space between the pipes A and B. From the chamber into which the oil is admitted it passes through holes 11 into the interior of the pipe B, the rear end of which is closed in any suitable manner. As here shown, it passes out of the oil-chamber through a suitable stuffing-box, as at 12, and screws into the hub of a hand-wheel 13, by which it can be advanced or retracted, for a purpose to be hereinafter 80 described.

The front block 3 has flanges 14 and 15, to the first of which the outer pipe A is screwed, and to the second one the tubular extension 16 is screwed, this extension carrying the 85 burner, as at 17.

The inner tube B is for convenience made with a screw-threaded joint or coupling, as shown at 18, so that it can be easily separated. When it is desired to take the burner apart by 90 disengaging the rear portion from the coupling and unscrewing the outer tube from the flange at 14, the two parts can be readily separated.

The space between A and B connects with 95 a converging passage 19 within the block 3 and exterior to a similarly-formed converging portion b at the front end of the pipe B. Within the pipe B is a central core 20 of sufficiently smaller diameter than the interior of B to leave an annular space all around it, and this core has a conical front end, as at 21, cor-

- responding with the interior of the block 3 and with the form of the portion *b* of the tube B, so that this arrangement provides for the annular convergent channel 19 opening from the space between the tubes A and B and conducting steam which is admitted through the passage 10 and a similar annular convergent channel between *b* and 21, which conducts oil flowing from the rear oil-chamber, to which it is admitted by the passage 9 through the space between the core 20 and the inner tube B. The core 20 may be hollow or solid, as preferred, and the front end of the core and also of the tube *b* are suitably supported and guided, so that they may be moved forward or back within the block 3. The tube B, which, as previously described, is connected with the hand-wheel 13, is advanced by turning the hand-wheel, the tube being screw-threaded where it passes through the diaphragm 24 or at other suitable point, and by moving it forward or back the steam-discharge channel 19 is varied. The core 20 passes out through the interior of the tube B and through its hub 13 and has fixed to its rear end a second hand-wheel 22. This core being also screw-threaded where it passes through the bracket 27 can be advanced and retracted independently of the pipe B, and in this manner the oil-passage between it and the parts *b* of the tube B can be varied with relation to the steam-inlet, as may be desired. The inner passage *b* opens into a centrally-disposed tube or chamber 23 in front of the block 3, and this is provided with holes or perforations through which the oil is discharged into the larger exterior chamber, which forms part of the burner 17, being thoroughly mixed in this chamber with the steam, which is first discharged from the passage 19 into a chamber formed by a diaphragm 24, which is screw-threaded on the periphery, so as to fit similar threads in the flange 15, and this allows it to be adjusted to increase or decrease the size of the chamber into which the steam is first discharged. From this chamber the steam passes through slots or openings 25 into the main mixing and burner chamber 17. The front end of the tube B where converged has a tubular extension 26, screw-threaded on the outside and turnable in similar threads in a hole made centrally through the diaphragm 24, and this supports the tube and allows it to be moved by turning the hand-wheel 13, so as to regulate the discharge-passage 19. The inner passage *b* is similarly regulated by advancing or retracting the core 20, the rear end of which (or its stem) is screw-threaded where it passes through the bracket 27 and provided with a suitable turning device 22. This construction allows the steam in the space between the tubes A and B to retain approximately boiler heat and pressure, and the oil in the inner passage between B and the cone is consequently more highly heated. The steam being hotter and drier makes a better mixture with the oil in the burner-chamber, from which it is delivered and ig-

nited through any desired form of exit-opening. To still increase the mixing capacity, a nozzle 28 is formed on the casting 16, its opening directing the mixture close to the burner-cap.

Having thus described our invention, what we claim, and desire to secure by Letters Patent, is—

1. The combination in an oil-burner of concentric tubes forming a steam-space, with an inlet at one end and a convergent discharge at the other, a core forming an annular space between itself and the inner tube said inner tube having the rear end connecting with the oil-inlet and the front forming a convergent discharge within and concentric with the steam-discharge, a mixing-chamber to receive the discharge from both tubes said inner tube having an extension beyond its convergent discharge and entering the mixing-chamber, and a perforated diaphragm between the mixing-chamber and the said convergent passages and adjustable toward and from said passages, and a burner connecting with the mixing-chamber.

2. The combination in an oil-burner of concentric tubes, a block consisting of a single casting having its body formed with steam and oil passages and having a projecting flange to which the rear end of the outer tube is screwed, said block having, also a central passage and stuffing-box through which the inner tube is movable; a cap fitting a rear flange of the block and forming a chamber at the rear of the block, said chamber communicating with the oil-passage in the block and said inner tube having perforations connecting with the oil-chamber, a block with which the front ends of the tubes are connected, a mixing-chamber into which the steam and oil are delivered at the front, discharge-openings and a burner inclosing the mixing-chamber.

3. The combination in an oil-burner of concentric tubes and interior cylindrical core having an annular space between it and the outer tube, a block consisting of a single casting formed integral with oil and steam passages and forwardly and rearwardly extending flanges, said outer tube connecting with one of said flanges and a cap fitted to the other flange and forming an oil-chamber between itself and the block said block having a passage through it for the inner tube and said inner tube having perforations connecting with said chamber, a stuffing-box carried by the block and through which the inner tube passes, a second block at the front of the tubes, having projecting flanges at both ends, to one of which flanges the front end of the outer tube is fitted, said second block having a convergent passage between itself and a corresponding front portion of the inner tube, a core movable within the inner tube said inner tube extended beyond the second block, a mixing-chamber on the extension of the inner tube, an adjustable and perforated diaphragm between the mixing-chamber and the

second block, and a burner connecting with the mixing-chamber.

4. In an oil-burner, the combination of inner and outer tubes, front and rear block to which the tubes are fitted, each of said blocks consisting of a single casting having front and rear extending flanges and one of said blocks having self-contained oil and steam passages, a cap fitted to the rear flange of the rear block and forming an oil-chamber communicating with said oil-passage, and said inner tube having perforations connecting with said chamber, a core passing through the inner tube means for operating the core and inner tube independently, means forming independent, convergent steam and oil passages at the front of the tube, a mixing-chamber in front of the tube and connecting with the inner tube, an adjustable perforated diaphragm between said chamber and the forward block, and a burner.

5. The combination in an oil-burner of an outer tubular chamber with blocks at opposite ends, an inner tubular chamber and a core concentric therewith, a mixing-chamber at the front with a perforated adjustable diaphragm in the rear, said diaphragm having a screw-threaded central opening through

which the extension of the main inner tube is guided and movable.

6. The combination in an oil-burner of concentric tubes having blocks at opposite ends and forming outer and inner chambers, a steam-passage opening through the rear block into the outer chamber and an oil-passage leading into the inner chamber, a cone-shaped opening in the front block, a corresponding cone-shaped portion at the front of the inner tube, a guide and means for advancing and retracting the inner tube to vary the steam-passage exterior to itself, a cone-headed core adjustable within the inner tube and the cone-shaped portion of the inner tube to vary the oil-passage, a burner-chamber with an adjustable diaphragm forming a supplemental steam-chamber with openings to admit steam to the burner-chamber, and a perforated head from which oil is delivered to meet the steam in said chamber.

In witness whereof we have hereunto set our hands.

LOUIS A. PFEIFFER.
LYMAN D. STAPLES.
